CLAIM

The ornamental design for an electrode patch, as shown and described.

DESCRIPTION

FIG. 1 is a perspective view of an electrode patch containing three electrodes;

FIG. 2 is a top plan view of the patch of FIG. 1;
FIG. 3 is a bottom plan view of the patch of FIG. 1;
FIG. 4 is a front elevational view of the patch of FIG. 1;
FIG. 5 is a back elevational view of the patch of FIG. 1;
FIG. 6 is a left side elevational view of the patch of FIG. 1;
and,
FIG. 7 is a right side elevational view of the patch of FIG. 1.
